ANIMATED TARGET

Irving D. Wallach, Port Washington, N. Y., assignor to Associated Development and Research Corporation, New York, N. Y., a corporation of New York

Application December 7, 1945, Serial No. 633,329

6 Claims. (Cl. 273—105.2)

1

This invention relates to amusement devices and particularly to apparatus in which targets are sequentially exposed at various locations within a restricted target area.

The invention is essentially an animated target intended for home amusement, although it can be modified for use in a standard shooting gallery wherein firearms are used. For purposes of the present discussion, however, the invention will be described as of the nature of a toy in connection with which the participants use toy guns or manually thrown missiles in an attempt to hit the several targets.

It is an object of the invention to provide an animated target in which one of several targets appear for brief intervals within a restricted target area.

It is an object of the invention to provide an apparatus of the class described wherein targets briefly appear in succession at one of three positions within the target area.

It is a further object of the invention to provide a mechanical target in which the appearances of the target devices are sudden and of brief duration, whereby the element of surprise adds to the normal enjoyment derived from the use thereof.

It is yet another object of the invention to provide a mechanical target in which the objects, when hit squarely, will drop out of the line of sight, and will ring a bell, for example, to denote such hit.

It is a further object of the invention to provide a mechanical target which is of simple and inexpensive construction and which will operate for long periods of time with substantial freedom from mechanical failure.

Other features and advantages will hereinafter be described.

In the accompanying drawings:

Fig. 1 is a front view of apparatus embodying the present invention, one of the targets being exposed in the target area;

Fig. 2 is a side elevation taken on lines 2—2 of Fig. 1;

Fig. 3 is a top plan view, in section, on lines 3—3 of Fig. 1;

Fig. 4 is a front elevation, similar to that of Fig. 1, but showing a second condition of operation of the apparatus; and

Fig. 5 is a plan sectional view of a target and target support, taken on lines 5—5 of Fig. 4.

Referring to the drawings, the apparatus comprises a case 10 which may be of plywood, composition board, or the like. The overall dimensions

2

are as desired; the depth is preferably suitable to receive the target operation devices and to provide a stable base without weighting the case or using additional structure to increase the base area.

The front panel 11 of the target has a preferably irregularly shaped opening 12 in the upper portion thereof, and a long, relatively narrow opening 14 along the lower margin, the latter opening serving as the means through which spent projectiles may roll out of the target case for re-use. The base wall 15 preferably slopes downwardly toward the opening 14, as shown in Fig. 2.

On a shaft 16 journaled in the front and rear walls of the case, there is secured a drive wheel 17 and a suitable target mount 18. The drive wheel 17 may be of wood, or of light metal sufficient to provide a flywheel effect, and is arranged to be rotated by electric motor means 20 suitably housed within the case, said motor being connected to wheel 17 preferably by belt drive operating through a suitable speed-reducing device designated in its entirety by the numeral 21. Electrical connections and switch means for drive and control of the motor, being conventional, are schematically shown at 22, Fig. 4.

A pair of swing-rods, respectively 24, 25, are secured to the freely pivoted shafts 26, 29. The rods are to the rear of and equidistantly on opposite sides of the center of wheel 17, and said wheel is provided, near its periphery, with an actuator pin 27, which comprises a fixed pin having a length which extends well to the rear of the said rods 24, 25, as shown in Fig. 2. Preferably the rods are interconnected by the spring 28, and to limit the swing of the rods toward each other, a stop 30, fixed to the rear wall of the housing, extends therebetween as shown in Figs. 3 and 4.

Assuming the wheel 17 to be rotated counterclockwise of Fig. 1 by the motor 20, the pin 27 will engage the rod 25 and will cause it to swing in a clockwise direction. The stop 30 prevents rod 24 from rotating conjointly with rod 25. As the pin 27 is moved through ninety degrees, the rod 25 will have been swung to its maximum, whereupon as the pin enters the lower quadrant of movement, the spring 28 maintains the rod in contact with the pin, and the rod therefore commences a return or counterclockwise rotation. As the pin approaches 180 degrees of rotation it will disengage from rod 25, and for a brief instant will be in engagement with neither rod 24 nor 25. Continued rotation brings the pin 27 into engagement with rod 24, swinging it out to

a maximum extent as the third quadrant is completed, and permitting the rod to return to original position as a revolution of the wheel 17 is completed.

The target support 18 is preferably a rectangular block or plate so positioned that its longer axis is coincident with a line extending from the pin 27 through the shaft 16. Hence, the target support is in vertical position when the pin 27 is at either zero or 180 degrees of its rotation. Targets 32 and 33 are hingedly carried at the ends of the target support, as shown in Figs. 1 and 2. A light spring 34 fixed to the rear of the target support bears against the rear of target 32, and a similar spring 35 bears against the target 33. These springs are only of sufficient strength to maintain the respective targets in the plane of the target carrier, but permit the respective targets to fall rearwardly upon being squarely struck by a missile.

The target support 18 carries a pair of bells or other noise producing devices, respectively 36, 37, said bells being in the path of movement of strikers 38 and 40, on the respective targets. Hence, as the target 32 swings rearwardly under impact, the striker 38, for example, will hit against the bell 36.

The sight area of the space 12 in which the targets 32, 33 appear, and the speed of rotation of the target support 18, are such that the respective targets will not return to vertical position while still within the sight area; the speed of rotation of said support of the targets also creates sufficient centrifugal forces to assist the springs to return the targets to operative position.

Shafts 42, 43 are suitably freely journaled in bearings at the upper right and upper left hand corners of the case respectively. Disposed substantially in the plane of the rod 24 is a short lever 44 pinned to the shaft 42 for rotation therewith. The said lever 44 is connected by a stiff, freely pivoted link 45, to the rod 25. Similarly, a lever 46 fixed to the shaft 43 is connected by a stiff link 47 to the rod 24. Pinned or otherwise secured to the shaft 42 is a target support arm 48, and similarly secured to the shaft 43 is a target support arm 50. As clearly appears in Fig. 2 the said target support arms 48 and 50 are adjacent the front wall of the housing. Preferably, a cloth curtain or the like 51 is hung from the top wall of the housing and extends downwardly to adjacent the base thereof, to conceal the operating mechanism from view and to act as a back-stop against which the projectiles, balls, or the like strike when no hit is made on a target.

Hingedly supported along an edge of the target arm 48 is a target 52, and a target 53 is similarly supported along the edge of target arm 50. Springs 54, 55 respectively hold the targets 52, 53 normally in a plane parallel to the front wall of the housing. These springs, like the springs 34, 35 are of relatively limited strength and offer little restraint against the rearward swing of the target upon the same being hit. The respective targets 52, 53 have strikers 56, 57 which hit against bells or the like 58, 60, carried on suitable brackets secured to the respective arms 48, 50.

As with the targets 32, 33 the spring supporting the targets 52 and 53 are of such strength that only a full hit will cause them to swing sharply rearwardly to sound the bell or other device. Also, the speed or swing of the respective target support arms is such that air resistance,

plus centrifugal force, assists the springs in returning the targets to operative position.

When one of the targets 32 or 33 occupies the sight area, as in Fig. 1, neither the target 52 nor 53 will be exposed to view; for in such instant of operation the pin 27 is not in engagement with either of the rods 24 or 25. The said rods being held in vertical position by the spring 28 and stop-block 30, the links connecting the rods with the respective levers 44 or 46 hold the levers and their respective target assemblies in concealed position. The spring 28 is sufficiently strong to prevent the pull of gravity from bringing either of the arms carrying targets 52 and 53 into a vertical position. By the time the pin 27 has sufficiently engaged rod 25, for example, to rotate it sufficiently to bring the target 52 into view, the target 32 has become concealed behind the front panel 12. Before the target 33 comes completely within the target area the rod 25 will have returned to substantially vertical position and will have returned its target to a point of concealment.

It is apparent that the order in which the targets are presented within the area 12 comprises 32, 52, 33 and 53.

The targets appear for only an instant, and with the exception of targets 32 and 33 no target occupies exactly the same space within the area. 30 The speed with which the successive targets are presented at successively different locations within the target area affords an element of surprise, adding to the enjoyment derived from the device.

The front wall 11 is preferably painted or scenically decorated consistent with the character of the individual targets. For example, painted trees or the like adjacent the positions at which the animal heads appear in the sight area, provide the illusion of such an animal "popping" from behind a tree, boulder, or the like.

Although the invention has been described by making a fully detailed reference to the certain presently preferred embodiments, such detail of description is to be understood in an instructive rather than a limiting sense, many changes being possible within the scope of the claims hereto appended.

I claim:

1. A target device, including a casing having an opening in one of its walls to provide a sight area which is relatively small in comparison with the wall area; a drive wheel rotatably mounted within said casing; means for rotating said wheel; an arm pivotally mounted within said casing and extending adjacent said drive wheel; target carrier means pivotally disposed within said casing remote from said sight area, the arc of movement of said target carrier means having one terminus within said sight area; a target affixed to said target carrier means and swingable thereby into and out of said sight area; link means connecting said arm and said target carrier means; actuator means on said drive wheel engageable with said pivotally mounted arm over substantially one half rotation of said drive wheel to oscillate said arm and said therewith associated target carrier means over an arc sufficient to expose said target to a maximum extent within said sight area at substantially one quarter revolution of said wheel and to remove the target completely from said sight area at substantially one half revolution of said wheel; and a second target carrier within said housing and rotatable by said drive wheel; a target mounted upon said second carrier and movable into and

out of view within said sight area substantially ninety degrees out of phase with said first named target, whereby at most, only a small portion of each target is exposed to view within said sight area at the same time.

2. A target device, including a casing having an opening in one of its walls to provide a sight area which is relatively small in comparison with the wall area; a drive wheel rotatably mounted within said casing; means for rotating said wheel; a pair of arms pivotally mounted within said casing and extending adjacent said drive wheel respectively on opposite sides of the axis of rotation thereof; target carrier means for each of said arms and pivotally disposed remote from and on opposite sides of said sight area, the arc of movement of each said target carrier means having one terminus within said sight area; a target swingably affixed to each said target carrier means and movable thereby into and out of said sight area; means on each said target for yieldably holding the same in the plane of said sight area; link means connecting each said arm with its associated target carrier means, actuator means on said drive wheel engageable with one of said arms for substantially one half rotation of said wheel and with the other arm for substantially the other one half rotation, whereby to oscillate each said arm in succession, the oscillation of one arm bringing the target of the target means associated therewith into full view within said sight area at substantially the first ninety degrees of rotation of said wheel and removing it completely therefrom at substantially the second ninety degrees of rotation; the oscillation of the second arm bringing the target of its associated target means into full sight at substantially the third ninety degrees of rotation and out of sight at the fourth ninety degrees of rotation of said wheel; and a third target carrier within said housing and rotatable by said drive wheel, said last named target carrier having targets mounted on the opposite ends thereof and movable into and out of sight substantially ninety degrees out of phase with said first named two targets, whereby when one target is completely exposed to view within said sight area, no part of any other target is simultaneously visible.

3. A target device as in claim 2, in which said

pivotaly mounted arms are mutually interconnected by spring means urging the said arms into rotation toward each other.

4. A target device as in claim 2, in which said pivotally mounted arms are mutually interconnected by spring means urging said arms into rotation toward said actuator means.

5. A target device as in claim 2, in which said pivotally mounted arms are mutually interconnected by spring means urging said arms into rotation toward said actuator means; said casing having stop means to restrain said rotation at a predetermined point.

6. A target device, including a casing having an opening in one of its walls to provide a sight area which is relatively small in comparison with the wall area; a plurality of target carriers pivotally mounted remote from the sight area, each target carrier having a target affixed thereto and swingable over an arc sufficient to bring said target into or out of said sight area; spring means for rotating each said target carrier in a direction away from said sight area; a stop for limiting said rotation and establishing a normal position in which the respective targets are out of said sight area; and means for moving said target carriers in reverse direction to bring the target thereon into said sight area, comprising a swing rod individual to each target carrier, said swing rods being pivotally mounted and each having a rigid link connecting with its associated target carrier; means mounted for rotation and engageable successively with each said swing rod for rotating the same and its associated target carrier in said reverse direction, and means for rotating said swing rod engaging means.
